UNITED STATES PATENT OFFICE.

JOHN E. STEVENS, OF KEWANEE, ILLINOIS.

GASOLENE-MOTOR.

1,084,977.

Specification of Letters Patent. Patented Jan. 20, 1914.

Application filed June 20, 1912. Serial No. 704,789.

To all whom it may concern:

Be it known that I, JOHN E. STEVENS, a subject of the King of England, residing at Kewanee, in the county of Henry and State of Illinois, have invented certain new and useful Improvements in Gasolene-Motors, of which the following is a specification, reference being had therein to the accompanying drawings.

10 This invention relates to internal combustion engines and has special reference to a novel form of valve for regulating the admission and exhaust of gases to and from such an engine.

15 One object of the invention is to improve the general construction of sleeve valves for use in connection with gasolene engines.

20 A second object of the invention is to provide a novel form of operating means 20 for such a valve.

With the above and other objects in view, the invention consists in general of certain novel constructions, combinations, and arrangements of parts, as will be hereinafter 25 fully described, illustrated in the accompanying drawings, and specifically claimed.

In the accompanying drawings like characters of reference indicate like parts in the several views, and Figure 1 is a central vertical section through an engine constructed 30 in accordance with this invention, certain of the parts being shown in elevation. Fig. 2 is a detail view of the valve showing the position of the ports. Fig. 3 is a view showing

35 a second position of certain cams shown in Fig. 2. Fig. 4 is a diagrammatic view showing the movement of the sleeve valve. Fig. 5 is a diagrammatic view of the cam lay out when the cams are in the position indicated in Fig. 2.

In the construction of this engine there is provided the usual crank case 10 whereon is mounted the cylinder 11 having a piston 12 reciprocable therein. The crank casing 5 is provided with suitable bearings to support the shaft 13 carrying a crank 14 which is connected to the piston 12 by means of a rod 15. This piston 12 is of less diameter than the cylinder 11 and between the cylinder and piston 12 there is fitted a sleeve 16. On the upper end of the cylinder there is provided a head 17 having a downwardly extending central portion 18 lying within the sleeve 16. The sleeve above referred to 55 forms the valve of the engine and has a double motion, that is to say, the sleeve has

both a reciprocatory and an oscillatory movement, the two being combined during a portion of the movement of the engine while at other times the reciprocatory movement alone is utilized.

The engine itself is provided with the usual intake passage 19 and exhaust passage 20, and in this instance these passages are preferably placed opposite each other where the intake has a chance to assist in the scavenging of burnt gases. The valve sleeve is provided with a series of exhaust ports 21. The exhaust and intake ports are so positioned that when one is open the other is closed.

The mechanism for opening and closing the exhaust and intake ports consists of a collar 23 which is secured to the lower end of the sleeve 16, the latter projecting into the crank casing. Through the crank casing extends a shaft 24 whereon is slidably mounted an eccentric 25 having an eccentric strap 26 surrounding the central portion of said eccentric. Extending upward from the eccentric is an arm 27 which is secured between lugs 28 formed on the collar 23. Fixed upon the crank case 10 is a pair of face cams 29 whose inner faces are parallel. Extending from each side of the eccentric 25 is a pin 30 having a ball head 31 which rests against the face of the adjacent cam. The shaft 24 is driven from the shaft 13 by any suitable gearing not deemed necessary here to be shown. The cams and eccentric are so positioned with relation to the movement of the sleeve 16 that during the intake or suction stroke of the engine the eccentric will be moving from the bottom to mid-position while the balls 31 will be rolling against dwells on the cams.

When the eccentric is rising for the compression stroke the cams are moving the eccentric to the right. During the firing stroke it is not desirable to move the sleeve 16 in a rotary direction and other dwells are provided on the cams over which the balls 31 travel while the eccentric is accomplishing the first half of its downward movement.

During the exhaust stroke the balls 31 are traversing the parts of the cam that cause the eccentric to move to the left while at the same time the latter is accomplishing the last half of its downward movement. This is clearly seen by reference to Fig. 4 which shows the movement of any point on the sleeve 16.

There has thus been provided a simple and efficient device of the kind described, and for the purpose specified.

It is obvious that many minor changes may be made in the form and construction of this invention without departing from the material principles of the invention and it is therefore not wished to confine the invention to the exact form herein shown and described but it is wished to include all such as properly come within the scope of the appended claims.

The valve sleeve is provided with a plurality of inlet ports which are formed similar to the exhaust ports 21, and these inlet ports are positioned upon the opposite side of the valve sleeve relative to the exhaust ports. These ports are arranged in position so as to allow the inlet ports to register with the inlet passage 19, while the exhaust ports 21 remain closed. As the valve sleeve reciprocates and oscillates within the cylinder 11, the inlet ports will close, while the exhaust ports 21 will register with the exhaust passage 20 for allowing the gases to escape.

Having thus described the invention, what is claimed as new, is:—

1. In a device of the kind described, a crank casing, an engine cylinder, a sleeve fitted within said engine cylinder and adapted to receive the piston of the engine, said sleeve being slidable and rotatable within the cylinder, the sleeve and cylinder being provided with ports adapted to register one with the other whereby the sleeve constitutes a valve, and means to oscillate and reciprocate said sleeve within said cylinder comprising a shaft, an eccentric slidable on said shaft, an eccentric strap surrounding said eccentric, an arm swiveled to said eccentric strap, a collar on said sleeve, lugs on said collar to which said arm is secured, a pair of face cams fixed on said crank case and provided with dwells arranged opposite each other, and pins projecting from said eccen-

tric and bearing against the faces of the respective cams.

2. In a device of the kind described, an engine cylinder, a sleeve fitted within said engine cylinder and adapted to receive the piston of an engine, said sleeve being slidable and rotatable within the cylinder, the sleeve and cylinder being provided with ports being adapted to register one with the other whereby the sleeve constitutes a valve, and means for oscillating and reciprocating said sleeve within said cylinder comprising a shaft, an eccentric slidable on said shaft, an eccentric strap surrounding said eccentric, an arm swiveled to said eccentric strap, a collar carried by said sleeve, said arm connected to said collar, and means coöperating with said shaft for operating said eccentric.

3. In a device of the kind described the combination with a crank casing, an engine cylinder, a sleeve fitted within said engine cylinder and adapted to receive a piston of an engine, said sleeve being slidable and rotatable within said cylinder, said cylinder and sleeve being provided with ports adapted to register one with the other whereby the sleeve constitutes a valve, and means for oscillating and reciprocating said sleeve within said cylinder comprising a depending arm attached to said sleeve, cams carried by said crank casing below and to one side of said sleeve, and means attached to said arm coöperating with said cams for imparting oscillating movement to said sleeve, and means coöperating with said last mentioned means for imparting reciprocating movement to said sleeve simultaneous with the oscillating movement.

In testimony whereof I hereunto affix my signature in presence of two witnesses.

JOHN E. STEVENS.
